(57) **CLAIM**

The ornamental design for a collapsible cart which functions as a transportable carrying box, as shown and described.

DESCRIPTION

FIG. 1 is a perspective view of a preferred embodiment of the collapsible cart which functions as a transportable carrying box, showing my design.

FIG. 2 is a front elevational view;

FIG. 3 is a rear elevational view;

FIG. 4 is a right side view;

FIG. 5 is a left side view;

FIG. 6 is a top plan view;

FIG. 7 is a bottom plan view; and,

FIG. 8 is a perspective view showing the collapsible cart which functions as a transportable carrying box in the collapsed condition.

The broken line showing of the hinges is included for the purpose of illustrating only and forms no part of the claimed design.
